UNITED STATES PATENT OFFICE.

DANIEL M. COOPER, OF ROCHESTER, NEW YORK, ASSIGNOR TO AMERICAN LAUNDRY MACHINERY COMPANY, OF CINCINNATI, OHIO, A CORPORATION OF OHIO.

LAUNDRY-PRESS.

1,073,890.

Specification of Letters Patent. Patented Sept. 23, 1913.

Application filed May 9, 1912. Serial No. 896,215.

To all whom it may concern:
Be it known that I, DANIEL M. COOPER, of Rochester, in the county of Monroe and State of New York, have invented certain 5 new and useful Improvements in Laundry-Presses; and I do hereby declare that the following is a full, clear, and exact description of the same, reference being had to the accompanying drawings, forming a part of 10 this specification, and to the reference-numerals marked thereon.

My invention relates to a controlling means for fluid pressure operated machines, having reference particularly to machines, 15 such as laundry presses, embodying a movable bed which is actuated by fluid pressure, and it has for its object the provision of a simple and conveniently arranged mechanism by which the operator can admit or 20 exhaust pressure to or from the pressure cylinder.

A further object of my invention consists in providing a construction by which a single actuating device serves to alternately admit and exhaust pressure to and from the pressure cylinder upon successive operations.

To these and other ends the invention consists in certain improvements and combinations of parts, all as will be hereinafter more 30 fully described, the novel features being pointed out in the claims at the end of the specification.

In the drawings: Figure 1 is a side elevation showing, partially, a laundry press embodying a preferred form of my invention; Fig. 2 is a vertical sectional view on the line 2^a—2^a of Fig. 1; Fig. 3 is a view in end elevation of the pressure cylinder and piston, the piston rod appearing in section; Fig. 4 40 is a sectional view on the line 4^a—4^a of Fig. 1; Fig. 5 is a detail sectional view similar to Fig. 4, the valve appearing in position to exhaust pressure from the operating cylinder; Fig. 6 is a horizontal sectional view on 45 the line 6^a—6^a of Fig. 1; Fig. 7 is a sectional view on the line 7^a—7^a of Fig. 2; Fig. 8 is a sectional view on the line 8^a—8^a of Fig. 4, and Fig. 9 is a sectional view on 50 the line 9^a—9^a of Fig. 4.

Similar reference numerals throughout the several figures indicate the same parts.

In the present embodiment, I have shown the invention in its application to a laundry press in which 1 designates the frame of the 55 machine, while 2 is the operating member, or

standard, which may be connected to a movable bed of the press, as usual in this type of machinery. The operating member 2 is connected to the links 3 which are in turn pivotally connected to the link 4, mounted on 60 the pivotal support 5. The toggle joint formed by the links 3 and 4 co-operates with the connecting rod 6, the latter being connected to the piston 7 which travels in the pressure cylinder 8. The cylinder 8 is provided with extensions 9 which are pivotally mounted on the beforementioned support 5, and it also carries a downwardly extending abutment 10 having a post 11 threaded therein and arranged to adjustably engage 70 the base 12. Upwardly extending arms 13 are provided to receive the adjustable posts 14, and by means of the posts 14; and post 11, the cylinder may be adjusted, and fixed rigidly with relation to the frame of the 75 machine.

The admission and exhaust of fluid pressure to and from the cylinder is controlled through the valve casing 15 which is connected with the cylinder by means of a passage 16, and with the atmosphere by means of the port 17. A pipe 18 connects with the valve casing 15 and is supplied with steam or other fluid under pressure in any convenient manner. Arranged within the 80 valve casing is the rotary valve 19 provided with inlet ports 20 which extend therethrough, and exhaust ports 21, each adapted to connect the passage 16 with the exhaust port 17, as shown in Fig. 5. The 85 inlet ports 20 are oppositely disposed, and the exhaust ports 21 are also oppositely disposed, being arranged between the inlet ports, as shown in Fig. 8. By this arrangement, as the valve is actuated, the inlet and 90 exhaust ports are alternately registered with the passage 16 leading to the cylinder, causing the operating member 2 to be successively raised and lowered. In order to effect the successive movements of the valve 95 by a single actuating member, I mount said valve on the rod 22, the latter carrying a ratchet wheel 23. Also mounted on said rod 22 is an arm 24 which carries the spring controlled pawl 25 arranged to engage the 100 ratchet wheel 23. The arm 24 is connected by a rod 26 to the rock arm 27 which extends from the treadle, or actuating device, 28. The treadle 28 is pivoted at 29 and carries a tail piece 30 for limiting its return 110

movement, and it is held in normal position, as shown in Fig. 1, by means of the spring 31 which connects with the extension 9. Complete control of the machine is had by merely depressing the treadle 28. When the valve is in the position shown in Fig. 4, upon actuating the treadle, the valve moves to the position shown in Fig. 5, causing the cylinder to be exhausted and lowering the operating member 2. The next movement of the actuating device moves the valve another step, bringing the ports again to the position shown in Fig. 4, and supplying pressure to the cylinders.

15 While I have shown and described a particular construction for accomplishing the purpose set forth, it will be understood that I am not limited to the exact arrangement shown herein, but intend to cover by this 20 application any modification which contemplates controlling a fluid pressure supply to a machine of this general type, by a single actuating device which, when operated, causes the fluid to be alternately supplied to and exhausted from the pressure cylinder.

25

I claim as my invention:

1. In a laundry press, the combination with a fluid pressure controlling cylinder

and a piston movable therein, said piston being connected to an operating member of the press, of a valve casing having a passage leading to the cylinder, a rotary valve and valve stem arranged in said casing, a ratchet wheel secured to the valve stem, a pawl in engagement with said ratchet wheel and a spring actuated treadle connected to the pawl.

2. In a laundry press, the combination with a fluid pressure controlling cylinder and a piston movable therein, of an operating member including a toggle joint having connection with the said piston, a valve casing having a passage leading to the cylinder, a rotary valve and valve stem arranged in said casing, the casing being disposed at the rear of the machine, a ratchet wheel secured to the valve stem, a pawl in engagement with said ratchet wheel, a rod having connection with the pawl and extending forwardly from the valve casing and cylinder, and a spring actuated treadle at the front of the machine pivoted to said connecting rod.

DANIEL M. COOPER.
